UNITED STATES PATENT OFFICE.

COURTENAY KINGSFORD, OF LONDON, ENGLAND.

STEAM-GENERATOR.

SPECIFICATION forming part of Letters Patent No. 268,690, dated December 5, 1882.

Application filed October 27, 1882. (No model.) Patented in England March 6, 1882, No. 1,078.

To all whom it may concern:

Be it known that I, COURTENAY KINGSFORD, of London, England, manufacturing chemist, have invented new and useful improvements 5 in and relating to steam-generators, chiefly designed for utilizing the waste heat of coke-ovens or the like, (for which I have obtained a patent in Great Britain, No. 1,078, bearing date 6th March, 1882,) of which the following is 10 a specification.

This invention relates to that class of steam generators or boilers in which an open flue passes longitudinally through the boiler, and a series of tubes or flues arranged to connect 15 the longitudinal flue with the boiler-shell, so as to form a series of lateral passages, and thereby admit of the entrance of products of combustion into the main longitudinal flue, whether the boiler is fired from underneath or 20 the fires made at each end of the longitudinal flue.

The object of my invention is to provide efficient and convenient apparatus for utilizing the waste heat arising from the combustion of fuel (in coke-ovens and other furnaces) for the 25 generation of steam for motive power or other purposes; and the said invention is designed to afford the means whereby manufacturers and others in whose factories the heat generated in various operations is now permitted to 30 escape without serving any useful purpose may make this heat serve for generating steam to drive engines, to heat water or other liquids, or for other purposes; so that the expense of 35 generating heat especially for such purposes may be entirely avoided. I accomplish this by constructing steam-generating apparatus as hereinafter described, and combining the same with a coke oven or ovens (or other furnace or furnaces) in such a manner that the 40 heat, instead of escaping directly from the latter, will first pass through and about the said apparatus.

My generator is illustrated in the accompanying drawings, in which Figure 1 represents a longitudinal vertical section of my improved steam-generator. Fig. 2 represents a plan of the same, and Fig. 3 an end elevation thereof; and Fig. 4 represents a partial verti-

cal longitudinal section of one of the water-chambers.

Like letters indicate the same parts throughout the drawings.

In carrying my said invention into practice in connection with a coke oven or ovens I propose constructing the steam generator or boiler with three cylindrical chambers or compartments, *a*, of any required length and diameter, each provided with a flue-tube, *b*, extending longitudinally through the same, as represented in Fig. 1. These cylindrical vessels or compartments *a* form the water chambers or spaces of the generator, and are connected by the pipes *c* with another cylindrical vessel, which forms the steam-chamber *d*, and which is arranged above and parallel to the said water-chambers. In two of the chambers *a*, I connect the longitudinal flue-tube *b* with the exterior shell of the chamber by means of flanged pieces or tubes to form flues or apertures *e* for the purpose hereinafter specified. The entire generator is inclosed in brick-work, either between the ovens in which the fuel is burned in the production of the coke or above the said ovens. The fuel is burned on the bed or bottom of the oven, and the heated air and products of combustion enter the flue-tubes *b* of the two side chambers at one end, and also through the flues or apertures *e*, and pass out at the other end of the flue-tubes *b*, and, returning through the flue-tube of the central chamber, they pass through one or more flues made in the brick-work or setting, and then escape through a chimney in the ordinary manner. Each aperture *e* is surrounded with a flanged piece or tube, *f*, riveted to the flue-tube and to the outer shell of the cylindrical chamber. These apertures may be arranged at the bottom or at the sides, or at both the bottom and sides, of one or more of the said water-chambers, as desired. Instead of a series of these apertures or flues *e*, I may form one long aperture in each of the said flue-tubes. The steam-generator above described is constructed entirely of boiler-plates.

Having thus described my invention, what I claim is—

A steam-generator consisting of the boilers

a, arranged side by side and connecting with a common steam-chamber, the said boilers each having a flue-pipe passing through it, which in one boiler is open only at its ends 5 for the purpose of finally carrying off the products of combustion, while in the remaining boilers a series of flues lead from the side of

the longitudinal flues to and through the boiler-shell, substantially as described.

COURTENAY KINGSFORD.
